[57] CLAIM

The ornamental design for a covered pillow, as shown and described.

DESCRIPTION

FIG. 1 is a top, front and right side perspective view of a covered pillow showing my new design;

FIG. 2 is a bottom, rear, and left side perspective view thereof;

FIG. 3 is a left side elevational view thereof; and

FIG. 4 is a right side elevational view thereof.

The cross-hatch surface shading employed is understood to indicate conventional fabric and is further understood to repeat uniformly across the surfaces represented.

FIG. 1

FIG. 2

FIG. 3

FIG. 4
